(57) **CLAIM**

The ornamental design for a game controller silicone cover as shown and described.

DESCRIPTION

FIG. 1 is a front, right, and top perspective view of a game controller silicone cover, showing my new design;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of an encircled area labeled "9" in FIG. 2.

The even length dash-dash lines depict portions of the game controller silicone cover that form no part of the claimed design. The dot-dot-dash lines in, FIG. 1, illustrate bounds of the claim and the long-short dash lines, in FIGS. 2 and 9, depict the bounds of the magnified portion that form no part of the claim.
